UNITED STATES PATENT OFFICE.

JOSEPH SUNNEN, OF MEXICO, MISSOURI.

VALVE-LIFTER.

1,369,142.

Specification of Letters Patent. Patented Feb. 22, 1921.

Application filed June 7, 1920. Serial No. 386,977.

To all whom it may concern:

Be it known that I, JOSEPH SUNNEN, a citizen of the United States of America, a resident of the city of Mexico, Audrian 5 county, and State of Missouri, have invented certain new and useful Improvements in Valve-Lifters, of which the following is a specification containing a full, clear, and exact description, reference being had to the 10 accompanying drawings, forming a part thereof.

My invention relates to improvements in valve lifters, and has for its primary object a valve lifter having its jaws constructed of 15 spring material so that by the tightening or loosening of a nut the jaws can be readily adjusted for different sized valve stems or washers.

A further object is to construct a valve 20 lifter having jaws in such a manner that when the same has compressed a valve spring, the spring can be held in that position any desired length of time.

In the drawings:

25 Figure 1 is a side elevation of my device showing the same applied to an engine valve.

Fig. 2 is an enlarged top plan view of my 30 device.

Fig. 3 a cross sectional view taken on the line 3—3 of Fig. 2.

Referring to the drawings, 4 indicates a portion of an engine cylinder, 5 the valve, 6 the valve stem, 7 the valve spring, 8 the washer against which one end of the spring rests, 9 the cotter key for holding the spring and washer on the valve stem, and 10 the upper end of the push rod, which operates the valve.

40 My improved valve lifter is constructed of two sections or jaws 11 and 12 which are preferably each of U-shape, having their forwardly extending ends 13 parallel with each other and united by the base or uniting 45 portions of the members 11 and 12. The forwardly extending substantially parallel portions of the jaw members 11 and 12 are preferably formed with inturned flanges 14 that form resting surfaces for the washer 8 on the valve stem and bearing surfaces resting against the push rod 10 or a surface of the cylinder 4, respectively. The base or doubled end of each jaw section is formed

with a lateral projection, that of the section 55 11 being designated 15, and that of the section 12, 18. One of these projections, the one designated 15, is formed with a pair of perforated ears 16, and these lie, when the parts of the device are assembled, opposite to and overlap the heel of the other jaw 60 section, and a pivot bolt or rivet 17 passing through these overlapping parts unites the two jaws. The extension 15 carries, near its heel, a threaded nut or boss 19, in which is adjustably seated a thumb screw 20, the 65 end 21 of which bears against the rear face 22 of the projection 18 near its outer end. It will be seen that the U-shaped jaw sections 11 and 12 lie one within the other and that the end of one of the lateral projections 70 75 is pivoted at its outer end to the other section where the lateral projection carried by such other jaw unites with the two parallel forwardly extending arms thereof. The parts 11 and 12 are preferably formed of sheet metal and hence can be easily shaped, and when thus made the forwardly extending arms thereof are resilient and hence capable of adjustment toward and from each other.

80 From this construction it will be seen that when the thumb screw 20 is driven inward the pressure exerted against the face 22 will spread the jaws 11 and 12; i. e., force them apart, and thus raise the washer 8 and compress the spring 7 when the key 9 can be withdrawn and the valve 5 removed from the engine cylinder. The jaws 11 and 12 are each provided with perforations through which a bolt 23 passes. This bolt is provided with the nut 24, and by either tightening or loosening this nut, the ends 13 of the jaws 11 and 12 can be either spread apart or drawn together, the spreading being caused entirely by the spring material 95 90 of which the jaws are composed.

With my device it is possible to remove the valve 5 from the engine without removing the valve lifter, and thus the washer 8 and valve spring 9 will also remain in their 100 proper positions, and there is no chance of losing the same, especially the washer, which is frequently done where the spring and washer have to be removed and laid on the work-bench before the valve is removed 105 from the cylinder.

Having fully described my invention, what I claim is:

A valve lifter, comprising a pair of substantially U-shaped members each such member being formed at its base with a lateral projection, and such sections lying one within the other at their base portions and united by a pivot connecting the outer end of one lateral extension with the base of the

other, and means for adjusting and holding the parts of the valve lifter with reference to each other whereby the free forwardly extending ends of the jaw sections are moved toward or from each other.

In testimony whereof, I have signed my name to this specification.

JOSEPH SUNNEN.
